CONTACT DEVICE

Russell Van Wijnen, Westmount, Quebec, Canada,
assignor to Schick Industries Limited, Nassau,
Bahama Islands, a corporation of Bahama Islands

Application October 21, 1937, Serial No. 170,134

9 Claims. (Cl. 200—30)

This invention relates to contact devices and particularly to contact devices for use under circumstances which require precise adjustment of the timing of a circuit in relation to a rotating body such as the armature of an impulse motor. It is among the objects of the invention to provide means for mounting one of the contact members of a contact device in a manner enabling variation of the position of impact of the contact points carried by the contact device whereby the timing of the electrical circuit controlled thereby may be varied as desired. This results in enabling accurate factory adjustment and affords simple and easily adjustable means for correcting for wear of the operating parts.

Another object of the invention is to provide in a contact device of the type wherein one of the contact members is continuously operated and the other contact member is relatively stationary, mechanism by which such a contact device is made capable of long use without the excessive wear which frequently affects devices of this type because of the impacts delivered against the stationary contact.

Another object of the invention is to provide a contact device and mounting means for securing the same upon a support or base made of Bakelite or equivalent condensation product and which is capable of prolonged use without such loosening of the mounting means as to impair the correct operating relationship of the parts of the contact device.

Further and other objects of the present invention will be hereinafter set forth in the accompanying specification and claims and demonstrated by the drawing which shows by way of illustration a preferred embodiment and the principle of my invention and what I now consider the best mode in which I have contemplated applying that principle. Other embodiments of the invention employing the same principle may be used and structural changes made as desired by those skilled in the art, within the spirit of the appended claims and without departing from the present invention.

In the drawing:

Fig. 1 is a plan of the contact device and its mounting.

Fig. 2 is a section on line 2—2 of Fig. 1 showing a section through the adjusting mechanism.

Fig. 3 is a view showing the upper portion of a contact member and a section through the cam or eccentric by which adjustment of position is accomplished.

Fig. 4 is a section on line 4—4 of Fig. 1 showing the supporting stud for the contact member.

The contact device of the present invention has advantages for controlling circuits of impulse motors and has particular utility with impulse motors of small sizes such as are used in shaving devices and in other hand tools employing portable motors. The efficiency of operation of an impulse motor is in part dependent upon the proper timing of the circuit which energizes the field coils. The energization of the field coils is usually accomplished by a contact device adapted to make and break the circuit under control of the rotating armature. For this purpose the armature shaft is provided with a cam mounted in definite angular relation to the armature to cause opening and closing of the circuit when the armature is in predetermined positions in respect to the pole pieces of the motor. The adjustment required for accomplishing this can be made in the factory when the motor is assembled but unless correction is applied from time to time, the timing of the circuit may change owing to the wear resulting from extensive use. The device of the present invention facilitates adjustment and correction of the timing of the circuit and makes the adjusting operation simple enough to understand for individuals lacking the skill of a factory technician.

In view of its particular suitability for a mechanical shaver, I have chosen to explain my invention in conjunction with such a device. In Fig. 1 I have illustrated the upper portion of a hollow handle 10 which constitutes a container or casing for the motor. The contact device includes a breaker arm 11 pivotally mounted upon a post 12, and a contact member 13 which is supported at its lower end upon a collar of another post in the form of a shouldered screw 14. The mounting for contact member 13 provides for slight motion upon impact from the breaker arm and angular adjustment about the axis of screw 14. Post 12 and screw 14 are mounted upon a base 15 which in the present embodiment of the invention consists of a block of Bakelite or equivalent condensate material.

This base has a thick solid portion 16 at its upper end which carries a journal bushing 17 for the pivot shaft 18 of a lever 19 by which the movable cutting element 20 of the shaver is operated. Depending from the upper portion 16 there are two thinner plate-like portions 22 and 23, between which the armature 24 of the motor is mounted. The front portion 22 carries a bearing 25 for shaft 26 of the armature and a

similar bearing is mounted in rear portion 23. The base is secured to the field magnet by bolts 27 engaging the rear portion of the base and the poles of the magnet.

5 Preferably the base is made in one piece so that journal 17 of pivot shaft 18 and the bearings for shaft 26 may be carefully positioned and the mounting of the respective shafts in parallel relationship assured. This is important because a 10 cam (not shown), which actuates the lower end of lever 19, is carried by armature shaft 26 and accurate mounting of the shaft 18 in respect to its driving member is desirable.

15 The center of shaft 26 is mid-way between a pair of field poles 28, 29 of the magnet.

The end of the armature shaft which extends beyond the outer surface of the front plate-like portion 22 of the base has a cam 30 by which the breaker arm 11 is operated. The breaker arm 20 may be of any conventional type, the one illustrated consisting of a sheet metal arm provided with a journal for engaging post 12. The free end of the breaker arm carries a contact point 31 made of tungsten or of other suitable material. This 25 contact point is adapted to close a circuit between the breaker arm 11 and contact member 13 through a cooperating contact point 32 which is carried by the contact member.

30 On the breaker arm, intermediate post 12 and the contact point 31, there is secured a rubbing block 33 having a bearing surface which cooperates with cam 30 and causes the intermittent rocking of the breaker arm. A spring 34 is provided for restoring the closed condition of the 35 contacts following each opening operation by the cam. One end of spring 34 is secured to the breaker arm and the other end abuts a post 35 which is mounted on base 15. The free end of the spring provides convenient means for attaching the conductor 36 which is connected with the coil of the field magnet.

36 The armature of the motor illustrated has two poles 37 and 38.

40 In the operation of the device, cam 30 on the armature shaft causes the breaker arm to be raised and contacts 31 and 32 separated twice for each revolution of the armature. When a high part of the cam passes rubbing block 33, spring 34 causes the breaker arm to snap back and bring 45 the contacts into contact with each other. In order to assure good electrical conduction between the contacts the low portions of cam 30 are preferably sufficiently low to clear the rubbing block and permit spring 34 to exert its entire 50 resilient force towards maintaining the contacts closed. As a result of this, it is apparent that contact 32 receives the full force of the impact produced by the release of the spring pressed breaker arm when the high part of the cam passes 55 the rubbing block. This is a desirable result because it tends to prevent filming between the contacting surfaces of the contacts and discourages the forming of oxides whose presence would otherwise impair electrical conductivity between 60 the contacts. On the other hand, the repeated and numerous impacts upon contact 32 might cause loosening of the mounting by which the contact is held in place, with the result that the timing of the opening and closing of the circuit 65 would be upset unless provision were made to avoid this result. As explained hereinafter, provision is made for absorbing without excessive shock the impact of the actuated contact.

70 75 In contact devices, much of the wear is likely

to occur at the contact points and between the rubbing block and actuating cam. Wear at either of these places will result in upsetting the timing of the circuit by changing the moments of making and breaking of the circuit at the contacts in 5 relation to the angular positions of the armature, so that following prolonged use, the motor will not operate as efficiently as it did when it left the factory in its proper adjustment. Loss of material on surfaces of the contact points results 10 in moving the line of contact toward the right (Fig. 1), with the result that for an armature rotating in a clockwise direction the contacts will be opened sooner and closed later as the wear increases. Any wear of the sliding surfaces of the 15 rubbing block and the actuating cam has the effect of causing the contacts to open later and to close sooner as the wear increases. These are of the sort of changed conditions which bring about changes in timing for which the device of 20 my invention can compensate to restore the most efficient operation of the motor. For accomplishing this end I have mounted contact member 13 in such a manner that the position of impact of contact point 32 may be varied.

25 In the present embodiment of my invention, the lower portion of contact member 13 is pivotally mounted upon a collar 39 of shoulder screw 40, Fig. 4. The upper end of contact member 13 is provided with a hole 40 (Figs. 2 and 3), in which 30 there is disposed a cam 41 in the form of an eccentric mounted upon a pin 42 which extends in and is made fast to the base 15 upon which the contact device is mounted. The top portion of the cam is provided with a knob 43 having a slot 44 therein by which the cam may be readily rotated to any desired position about the axis of the pin. Rotation of the cam upon pin 42 varies the angular position of the contact member 13 about its supporting post 14 and by rotating the cam 35 it is possible to change the normal position of impact of contact 32 and thereby change the moments of opening and closing of the circuit.

40 Under some circumstances the edges 45 and 46 of hole 40 may be so spaced as to always engage the periphery of cam 41 so that the cam would rigidly maintain the contact member in its set position at all times. However, the effect of the repeated impacts upon a fixed contact tends to loosen the mounting holding the contact in place, with the result that any loosening that may develop could cause disarrangement of the proper timing of the circuit and factory attention would be necessary to resecure the mountings and restore correct timing. I have therefore provided 45 means for resiliently absorbing the energy developed when the breaker arm is released and the contacts engage, and in order to accomplish this 50 I have provided a spring 48 (Figs. 1 and 2).

55 This spring may be secured to or turned up at right angles from a bracket 49, which is fastened to contact member 13 by such means as rivets 50, 51, or may be fastened by any other equivalent means, such as by welding. The free end of spring 48 rests against knob 43 and resiliently maintains contact member 13 against cam 41. The position thus maintained is the position in which contact 32 receives the impact from the contact on the breaker arm. In this position edge 46 of hole 40 is spaced from cam 41 (Fig. 3) so as to assure that the effect of the impact will be resiliently absorbed by the spring. Edge 45 of hole 40 is held against the cam as though it were an outside edge of the contact member.

As explained hereinabove, the position of impact of contact 32 may be varied by changing the angular position of cam 41 upon its supporting pin 42. In order to maintain the cam 5 in the position in which it is set, the upper end of spring 48 preferably is hooked so as to engage one or another of the longitudinal grooves 52 in the outer surface of knob 43. The spring thereby forms an abutment substantially 10 tangential to and against any rotary displacement of the knob and associated cam.

In addition to these functions, spring 48 acts 15 to maintain the cam and knob upon the pivot post with the cam opposite an edge of the contact member. To attain this end a flange or shoulder 53 is provided upon the cam and the inner side of this flange is held in engagement with the outer side of contact member 13 by the edge of spring 48 which is located adjacent 20 the outer side 54 of the flange. To remove the cam it is necessary only to flex spring 48 sufficiently to clear the periphery of flange 53 and then lift the cam from its supporting pin 42.

The flanges of rivets 50 and 51, which secure 25 the spring to the contact member 13, serve to maintain the contact member raised from the base 15 and also afford restricted bearing surfaces. A spring washer 56 (Fig. 4) engages rivet 51 and maintains the contact member in 30 position with the flange of the rivet bearing against the base upon which the contact member is mounted.

The contact member itself consists of a metallic plate having an end portion 57 turned-up 35 at right angles to the plate and bent back upon itself where it is welded or otherwise secured to the plate, as at 58. The turned-up portion 57 serves as a support for the contact point 32, but any other suitable form of support may be 40 provided.

When the contacts are closed the circuit is completed through conductor 36, spring 34, breaker arm 11, contacts 31, 32, contact member 13, a depending terminal 59 and conductor 45 to 60.

What is claimed is:

1. In combination, a contact device comprising a pivotally mounted breaker arm carrying a contact point, a contact member positioned for receiving impacts from said breaker arm, means supporting said contact member for pivotal movement, a contact point carried by said contact member and adapted to be intermittently engaged by the contact point on said breaker 55 arm for controlling a circuit, means for actuating said breaker arm, means resiliently supporting said contact member against the force of impact imparted by the breaker arm at each closing of the circuit, said means including a spring initially stressed and exerting pressure 60 upon the pivoted contact member against the direction of closing movement of the contact point carried by the breaker arm while enabling pivotal movement of said contact member as the 65 energy of impact is absorbed by said spring.

2. In combination, a contact device comprising a breaker arm pivotally mounted for actuation, a contact carried by said breaker arm, an adjustably positionable contact member, a contact 70 carried by said contact member and arranged for cooperation with said first named contact, means supporting said adjustably positionable contact member and enabling change in its position, said means including a cam, and 75 means resiliently urging the contact member

against said cam whereby shock of impact at the closing of the contacts is materially dissipated.

3. In combination, a contact device comprising a breaker arm pivotally mounted for actuation, a contact carried by said breaker arm, an adjustably positionable contact member, a contact carried by said contact member and arranged for cooperation with said first named contact, a base for supporting said breaker arm 10 and contact member, a post for pivotally supporting said contact member, said supporting post being mounted on said base, a cam engaging said contact member and capable of changing the position of the contact member about 15 its supporting post, means supporting said cam upon said base, and a spring carried by said contact member and having its free end in engagement with a portion extending from said cam, said spring serving to maintain the contact member against the cam. 20

4. In combination, a contact device comprising a breaker arm pivotally mounted for actuation, a contact carried by said breaker arm, an adjustably positionable contact member, a contact carried by said contact member and arranged for cooperation with said first named contact, a base for supporting said breaker arm and contact member, a supporting post for said contact member in engagement within a hole 30 in the contact member, said supporting post being mounted on said base, a pin also mounted on said base and extending through another hole in said contact member, a cam rotatably mounted on said pin, a spring carried by said contact member and having its free end in engagement with a knob extending from said cam, said spring serving to maintain the contact member resiliently against the cam to absorb energy of impact between the contact points, means 40 on said knob for engaging said spring to prevent change in the setting of the cam, said means being grooves normal to the plane of rotation of the cam, and a shoulder carried by the cam, said shoulder being engaged by the spring to 45 maintain the cam upon its supporting pin.

5. In combination, a contact device comprising a breaker arm pivotally mounted for actuation, a contact carried by said breaker arm, an adjustably positionable contact member, a contact carried by said contact member and arranged for cooperation with said first named contact, a base for supporting said breaker arm and contact member, said base being of one-piece and consisting of a condensation product, a post for 55 pivotally supporting said contact member, said supporting post being mounted on said base, a cam engaging said contact member and capable of changing the position of the contact member about its supporting post, means supporting said cam upon said base, and a spring carried by said contact member and having its free end in engagement with a portion extending from said cam, said spring serving to maintain the contact member against the cam. 60

6. In combination, a contact device comprising a pivotally mounted breaker arm carrying a contact point, an adjustable contact member, a contact point carried by said adjustable contact member and adapted to cooperate with the 70 contact point on said breaker arm for controlling a circuit, means for actuating said breaker arm, means supporting said adjustable contact member and enabling variation of its position and the position of impact of the contact 75

points, said means including a pivot post for the contact member and a cam cooperating with said contact member, and means carried by said contact member and acting upon the cam for locking the same in set position while enabling yield between the contact member and cam upon impact of the contact points.

7. In combination, a contact device comprising a pivotally mounted breaker arm carrying a contact point, an adjustable contact member, a contact point carried by said adjustable contact member and adapted to cooperate with the contact point on said breaker arm for controlling a circuit, means for actuating said breaker arm, means supporting said adjustable contact member and enabling change in its position for receiving impacts from the breaker arm, said supporting means being capable of positive determination of selected impact positions of the adjustable contact member, and self-locking means cooperating with said supporting means for normally holding said supporting means and adjustable contact member in selected positions.

8. In combination, a contact device comprising a pivotally mounted breaker arm carrying a contact point, an adjustable contact member, a contact point carried by said adjustable contact member and adapted to cooperate with the contact point on said breaker arm for controlling a circuit, a base supporting said adjustable con-

tact member, means for intermittently actuating said breaker arm for causing engagement of the contact points, means cooperating with said adjustable contact member for determining the position in which it is to receive impacts from the breaker arm, and a spring carried by said contact member and engaging said position-determining means, said spring serving to bias said contact member and position-determining means into engagement with each other while also cushioning said supporting base from the shock of impact between the contact points.

9. In combination, a contact device comprising a breaker arm pivotally mounted for actuation, a contact point carried by said breaker arm, an adjustably positionable contact member, a contact point carried by said contact member for cooperation with said first named contact point, a base supporting said adjustable contact member, a rotatably settable cam cooperating with said adjustable contact member for determining the position in which the contact member is to receive impacts from said breaker arm, means for supporting said cam upon said base, a spring engaging said cam, said spring serving to bias the contact member against the cam, and means engaging said cam and spring whereby the cam is held on its supporting means by the spring.
